UNITED STATES PATENT OFFICE.

CHARLES S. BATDORF, OF BROOKLYN, NEW YORK, ASSIGNEE TO AUTOMATIC COIN-WRAPPING MACHINE COMPANY, A CORPORATION OF NEW YORK.

COIN-SORTING AND COMPUTING MACHINE.

1,103,124.

Specification of Letters Patent.

Patented July 14, 1914.

Application filed February 11, 1913. Serial No. 747,596.

To all whom it may concern:

Be it known that I, CHARLES S. BATDORF, a citizen of the United States, and a resident of Brooklyn, in the county of Kings and State of New York, have invented certain new and useful Improvements in Coin-Sorting and Computing Machines, of which the following is a specification.

One object of the invention is to provide a thoroughly efficient machine with the use of which a cashier or other person receiving varying quantities of coins of various denominations indiscriminately mixed or jumbled together, may quickly sort out or separate the coins of the respective denominations and discharge them into separate bags or receptacles, preparatory to said coins being suitably wrapped by coin-wrapping machines.

20 A further purpose of the invention is to provide a machine of the character referred to, having means thereon for separately counting the coins of each denomination passing through it and of separately computing, registering or indicating the value of all the coins of each denomination thus counted.

25 A further object of the invention is to provide a machine of the character referred to which will discharge the sorted coins one after another of each denomination and discard or throw out from the discharging coins of one denomination any coin of a different denomination that may by accident or otherwise have become intermingled therewith.

30 The machine of my invention comprises, in the preferred embodiment thereof, a series of perforated plates or screens arranged one partly below and projecting beyond the other in series and each adapted to retain coins of one denomination and permit all smaller coins to pass through it, a bottom non-perforated plate to receive from the 35 perforated plates above the coins of the smallest size used, such as ten cent pieces, independent chutes for the discharge of the coins arrested on the respective plates, receptacles or compartments connected with the 40 respective chutes for receiving the coins therefrom, means for emptying said receptacles or compartments into separate bags or the like, means at each chute for compelling the passage therethrough of the coins, 45 one after another, of one denomination and

discarding or throwing out any coins of a different denomination which may by accident or otherwise have entered the chute, means at each chute for counting the coins discharged through the same, and means at 50 each chute for computing and registering the total value of all the coins passing through the same during any stated period.

55 The machine of my invention is particularly useful to corporations and persons receiving coins of varying denominations in large quantities or in varying quantities from different individuals aggregating large quantities at stated periods, as for illustration the owners of street-car lines whose "conductors" individually bring in varied assortments of coins which must for each conductor be counted and the amount thereof compared with the register slip or record of the car. With the use of my machine the 60 coins handed in by each conductor may be sorted and discharged into separate receptacles and the value thereof quickly ascertained for comparison with the register slip or record of the car. In the continued use 65 of the machine the coins of each denomination may be kept together during any stated period and delivered to banks having coin wrapping machines by which the coins are wrapped into packages of predetermined 70 values. My machine enables the ready sorting of the coins of each conductor and the computing of the total value thereof for comparison with his record, and in addition the coins of each denomination passing 75 through the machine are counted and hence the total value of each denomination of coins and the total value of all the denominations of coins passed through the machine during 80 any stated period may be readily computed.

85 The invention will be fully understood from the detailed description hereinafter presented, reference being had to the accompanying drawings, in which:

90 Figure 1 is a side elevation, partly broken away and partly in section, of a coin sorting and computing machine constructed in accordance with and embodying my invention; Fig. 2 is a front end view of the same, taken from the right hand end of Fig. 1; 95 Fig. 3 is a vertical transverse section through the same, taken on the dotted line 3-3 of Fig. 1; Fig. 4 is an enlarged detail, partly broken away, of a portion of the machine, and designed to illustrate more clearly than 100

the same is represented in Fig. 1, the means for counting the coins leaving the machine at each section or screen-plate thereof and computing or totalizing the amount or value represented by such coins; Fig. 5 is a horizontal section of the same, taken on the dotted line 5—5 of Fig. 4; Fig. 6 is a like section of a portion of the same taken on the dotted line 6—6 of Fig. 4; Fig. 7 is a vertical transverse section through a portion of the same, taken on the dotted line 7—7 of Fig. 6; Figs. 8 and 9 are vertical sections through a portion of the computing mechanism and illustrate two different forms of the cams that may be employed therein, Fig. 8 showing a cam having one trip and conveniently used in the computing mechanisms for the screen-plates from which ten-cent pieces and pennies discharge and are counted, and Fig. 9 illustrating a cam having five trips and adapted for convenient use in the computing mechanisms for what we may call the quarter or twenty-five cent and five-cent screen-plates or the plates on which twenty-five cent pieces and five-cent pieces are respectively caught and from which they are discharged and counted. The number of trips present on the cams shown in Figs. 8 and 9 is a matter wholly within the desire of the manufacture and the order of the numerals used on the counting disks; Fig. 10 is a top or plan view of a portion of the machine, and Fig. 11 is a vertical section through a portion of the same on the dotted line 11 of Fig. 10.

In the drawings 15 designates an exterior box-like casing to be supported upon a suitable table or the like, not shown, preferably containing drawers for the reception of money. The casing 15 at one side has the formation of a series of steps (Fig. 2), and said casing supports a series of perforated plates, numbered respectively, 16, 17, 18 and 19 and a non-perforated plate 20, the upper plate 16 being horizontal throughout and extending from the front to the rear of the casing 15 and across the width of the upper portion thereof except at one front side edge at which the screen is deflected downwardly, as at 21 (Fig. 3), to direct coins to a vertical chute or hopper between an outer plate 22 and an inner plate 23 to be hereinafter more fully referred to. The perforated plates 17, 18 and 19 and plate 20 have horizontal outer side portions, as clearly represented by the dotted lines in Fig. 2 and by solid lines in Fig. 3, and at their inner portions said plates incline upwardly, one below the other, and thereby form chutes leading downwardly to the horizontal portions of said plates, said inclined portions of the plates being separately numbered, for convenience of identification, 24, 25, 26 and 27 respectively, and preferably perforated with the exception of the portion 27 which, like

the horizontal portion of the plate 20, is not perforated, it not being intended that any coins shall pass through the plate 20 or its inclined portion 27. The horizontal portions of the plates 17, 18, 19 and 20 project laterally one beyond the other in descending series, and the plate 17 projects laterally beyond the plate 16, and thus the upper surface of the plate 16 is fully exposed and substantial portions of the plates 17, 18, 19 and 20 are exposed for the hand manipulation of the coins that may be placed or arrive thereon and the detection of counterfeit and mutilated coins.

The plates 16, 17, 18 and 19 are perforated or formed with openings intended to permit certain coins to pass through them and prevent other coins differing in size from passing through them, and in the present instance it is intended that a collection of fifty cent coins, twenty-five cent coins, five cent coins, one cent coins and ten cent coins will be dumped or placed upon the upper perforated plate or screen 16 whose openings are of such size that all of the coins except the fifty cent coins will pass through the plate while the fifty cent coins will remain on the plate, the openings in said plate being too small to permit of the passage therethrough of fifty cent coins. All of the coins falling through the plate 16 will pass upon the plate 17, and all of such coins with the exception of twenty-five cent coins will pass through said plate 17, the twenty-five cent coins being retained thereon. All of the coins falling through the plate 17 will descend upon the plate 18 and all of such coins with the exception of five cent pieces will pass through said plate 18, the perforations or holes in said plate being proportioned to permit all coins, smaller in size than the five cent pieces, to pass through them and to prevent five cent pieces from passing through them. The coins which pass through the plate 18 will fall upon the plate 19 whose perforations are of such proportion that the plate will retain one-cent coins and permit the passage through it of ten cent coins, the ten-cent coins falling through to and temporarily remaining upon the plate 20. The variety of coins that might be received by the conductor of a street car are thus all placed on the plate 16 and sorted out by the various plates into lots of fifty-cent coins on the plate 16, twenty-five cent coins on the plate 17, five-cent coins on the plate 18, one-cent coins on the plate 19, and ten-cent coins on the plate 20, and thereafter the said coins are, by the means presently to be described, discharged into separate compartments and finally reach separate bags or receptacles, and said coins are at the same time or during their discharge into said compartments counted and the amounts of the separate denomina-

tions totalized or registered automatically, so that at the end of any period the number of coins of each denomination and the value of all the coins of each denomination that have passed through the machine during said period may be quickly ascertained.

At the outer or left hand side, looking at Fig. 2, of each step formation of the machine and just below and communicating with one of the plates 16, 17, 18, 19 and 20, is formed a hopper, the separate hoppers being, for convenience of identification, numbered respectively 28, 29, 30, 31 and 32, and said hoppers being vertically disposed and of the proper respective widths to snugly receive on edge proper coins of the denominations arrested on the respective plates discharging into them and having inclined bottoms, as denoted at 33, in Fig. 1. The hoppers are formed between plates, all corresponding with the plates 22, 23 numbered for the upper hopper 28 in Fig. 3, and the outer plate 22 being of glass so that the coins may be observed therethrough. The hoppers 28, 29, 30, 31 and 32 are only at the forward portions of the sides of the plates 16, 17, 18, 19 and 20 and each one receives the coins retained on the plate adjacent to which it is located, said coins being the ones which did not pass through the plate and in the use of the machine being brushed manually over the edge of the plate and into the hopper. As hereinbefore explained, the forward side edge portion of the upper plate 16 is deflected downwardly, as at 21, so that the coins brushed over the forward side edge of said plate may tilt and readily enter the hopper 28. The plates 17, 18, 19 and 20 are at their forward side edges also deflected downwardly, as at 34 (Fig. 3) to enable the convenient passage of the coins, manually brushed over the edges of the plates, into the respective hoppers 29, 30, 31 and 32. The coins when on the plates 16, 17, 18 and 19 will be brushed about by the fingers of the attendant so that all of the coins not intended to remain on the respective plates may descend through them, and thereafter the coins which remain on the respective plates are in the use of the machine brushed laterally to the side deflected portions 21, 34 and thereby caused to enter the respective hoppers, from which they are one after another discharged.

At the lower front edge of each hopper 28, 29, 30, 31, 32 is an auxiliary downwardly inclined discharge chute 35 (Figs. 1 and 4) of just about the height of the coins intended to pass on edge through the same. The chutes 35 correspond with each other, except that the upper chute is of vertical height sufficient for the passage therethrough of fifty-cent pieces, while the next lower chute is of a height to permit the snug

passage through it of twenty-five cent pieces, and the next lower chute of a height required for five-cent pieces, and the next lower chute of a height required for the passage of one-cent pieces and the bottom chute 70 of a height required for the passage of ten-cent pieces. Each chute is formed with a lower vertical shoulder 36 behind which the lower edges of the coins travel and an upper depending flange 37 behind which the upper portions of the traveling coins pass and which shoulder and flange serve to retain the coins on edge and to direct them downwardly to, at each chute, a rubber-tired roller or wheel 38 by which the coins are 80 forced from the chute and into a receptacle, presently to be described. All of the rollers 38, there being one for each chute 35, are in constant rotation, their vertical shafts numbered 39, being driven through any suitable 85 intermediate mechanism (Fig. 3) from a motor 40 of commercial character. When the coins roll down the chutes 35 they pass to the outer edges of the gripping or elastic rollers 38 and are by said rollers forced 90 along the chutes 35 and from the front end thereof. I cut away a portion of the flange 37 of each chute 35 directly above the roller or wheel 38, thereby leaving a recess 41 extending nearly to the top of the chute, and this is to enable the said roller or wheel to, should an improper coin or one less in height than the predetermined coin intended therefor enter the chute, by its pressure against the same, tilt the coin outwardly 100 from the chute, the upper edge of such coin being left unbacked at its upper edge at the recess 41 and thus rendered incapable of continued travel along the chute when the pressure of the roller or wheel 38 is exerted 105 against it. The wheels 38 have therefore for their purposes the forcing of the coins along and their discharge from the delivery end of the chutes 35 and to discard or force laterally from the chutes any coins of one 110 denomination which might by accident or otherwise enter a chute or guideway 35 intended for coins of a different denomination. As shown in Fig. 4, the top of the chute or guideway 35 is slightly higher than the upper edge of the recess 41 and hence coins of the proper size extending as they do above the said recess will not be discarded by the roller 38 and caused to fall on the next lower screen but being retained at their upper and lower edges will be forced by said roller to travel along the chute or guideway. Adjacent to the lower end of each chute or guideway 35 is a receptacle to receive the 125 coins discharged therefrom, and these receptacles are all alike in construction and numbered, respectively, 42, 43, 44, 45 and 46, each of the receptacles being a box-like structure preferably having an outer man-

ually operative hinged door 47 and an interior downwardly inclined hinged floor 48. The coins enter the receptacles 42, 43, 44, 45 and 46 from the chutes 35 and fall upon the floors 48 thereof and remain thereon until either said floors are swing downwardly, as indicated by the dotted lines at the lower right hand portion of Fig. 1, for the discharge of the coins, or until the doors 47 are opened and the coins permitted to slide out into the hand of the operator or into a suitable receptacle. Ordinarily it will not be necessary to open the doors 47 since the purpose is at the proper time and after an assortment of coins has passed through the machine and into said receptacles, to open or turn the bottoms 48 downwardly so that the coins thereon may fall into suitable bags 49 (Fig. 2) detachably hooked upon the lower ends of the receptacles to receive them. It may be, however, that a conductor will bring in an assortment of coins which when caused to pass through the machine to the receptacles 42, 43, 44, 45 and 46 will not tally on the record made on the computing wheels, hereinafter referred to, with the statement or record slip presented by him, and in that event the operator may open anyone or more of the doors 47 and count the coins to verify the figures given on the computing wheels or permit the conductor to count the coins over again and thus detect the error, should one exist, in his statement or record slip of the amount thereof.

It is desirable that the several receiving receptacles for coins have doors 47 so that at any time an occasion therefor should arise, the coins may be withdrawn from the receptacles without causing the bottoms 48 of the receptacles to drop the coins into the bags 49. I provide the front face of each receptacle, directly below, the door 47, with a downwardly and outwardly inclined lip 50 (Fig. 1) in line with the bottom 48 of the receptacle to coöperate with said bottom in conveniently allowing the coins to slide outwardly from the receptacle when the door 47 is opened.

The means provided by me for turning the floors 48 downwardly contemplate simultaneous action in said floors, and for convenience I provide a crank arm 51 on each shaft hinging said floors 48 at their upper ends, as shown by dotted lines in Fig. 1; and connect all of these crank arms by means of vertical rods 52 with a bar or treadle 53, which, when depressed, will pull all of the crank arms 51 downwardly and cause all of the floors 48 of the receptacles to swing downwardly and discharge the coins that had been held thereon into bags 49 placed to receive the same.

Adjacent to the discharge end of each chute 35 I provide a counter 54 of usual type for counting the coins discharged

through the end of the chute and also a computing mechanism, shown on an enlarged scale in Fig. 4, for indicating the total value of the coins discharged through the chute during any stated period. It is my purpose that the counter 54 shall, for instance, count all of the coins passed through the chute during an entire day and that the computing mechanism may give the total value of each assortment of coins passed through the chute that a conductor might bring in, so as to render it convenient to compare the computation given by said mechanism with the statement handed in by the conductor of the value of the coins delivered by him. The counter 54 for each chute would, under the circumstances mentioned, be set back to "0" each morning, while the computing mechanism would be turned back to "0" after each assortment of coins had passed through the machine. The counter 54 and computing mechanism for each chute 35 are actuated by the coins on their travel through the chute, said coins being utilized to rotate, by a step-by-step movement, a toothed wheel 55 secured on a shaft 56 and projecting at its lower edge in the path of the coins forced along the chute 35 by the wheel 38, as shown in Fig. 4. Each coin as it passes the wheel 55 will rotate said wheel one predetermined space or notch, and this movement of the wheel 55 will be communicated through a bevel gear wheel 57 to a corresponding gear wheel 58 and thence to the shaft 59 of the counter 54, said counter being of the Veeder type and adding one unit on the wheels with each rotation of the shaft 59. I make no separate claim for the counter 54 since it is of well known form and construction. The rotation of the wheel 55 and shaft 56 is also communicated through a pinion wheel 60 on said shaft, to a gear wheel 61 constituting a portion of the computing mechanism, as will be readily understood on reference to Figs. 4, 5 and 6. The wheel 61 will preferably have one hundred teeth in its periphery and the pinion wheel 60 ten teeth, and the wheel 61 is mounted upon a sleeve or tubular shaft 62 journaled in the side 63 of the machine. The wheel 61 has secured upon its inner face a cam 64 and this cam is co-operatively employed with a ratchet 65 having one-hundred teeth and secured upon the inner end of the sleeve or tubular shaft 62 and arranged to be acted on by a pawl 66 carried at the upper end of a pivoted arm 67 having a toe member 68 which is kept in engagement with the periphery of the cam 64 by means of a spring 69. The spring 69 exerts a tension against the upper end of the arm 67 tending to retain the pawl 66 against the ratchet wheel 65 and the toe member 68 against the periphery of the cam 64. The cam 64 shown in Fig. 8 is formed at one point of its periphery with a trip or shoul-

der 170, and when at the end of a rotation of said cam said shoulder reaches the toe 68 of the arm 67 the spring 69 will cause said toe to instantly move inwardly over said trip and against the depressed portion of said cam, with the result that the pawl 66 will be driven forwardly against the ratchet wheel 65 and cause said wheel to rotate one space. Each coin actuating the wheel 55 will cause the gear wheel 61 to turn one space, but it will require a complete rotation of the cam 64 of Fig. 8 to effect through the arm 67 and parts carried thereby, the rotation, to the extent of one space, of the ratchet 65. Thus pennies or other fractional dollar values may be counted up on the wheel 61, while a dollar or multiple thereof may be represented by each separate movement of one space of the ratchet wheel 55. The cam 64 is, as aforesaid, secured to the wheel 61, and the ratchet wheel 65 being rigid with the tubular shaft or sleeve 62, rotates a disk 70 which is keyed upon the outer end of said shaft 62 and formed with a knob 71 by which it may be manually rotated or set back to its "0" position whenever desired. Upon the face of the disk 70 is a line of numerals 72 denoting dollars arranged to line up with the series of transverse lines of numeral characters on the face of the wheel 61 denoting fractional parts of a dollar (and dollars also when desired) as is customary in registering mechanisms.

During the passage of the coins through a chute 35 each intermittent rotary movement of the wheel 55 caused thereby operates the counter 54 and imparts movement to the wheel 61 and cam 64 and at each pre-determined period of the rotation of the cam 64 the pawl 66 is actuated to rotate the ratchet 65 and through said ratchet and tubular shaft 62 the disk 70 one space. The cam 64 with one trip 170 shown in Fig. 8 will be used in the computing mechanisms at all the chutes 35 except those through which five and twenty-five cent pieces pass and in said two mechanisms I will provide the cam with five corresponding equally spaced trips, as shown in Fig. 9, so that the ratchet wheel 65 and disk 70 may be turned one space as each of said trips pass the toe 68. The counter and computing mechanisms at all the chutes 35 are essentially alike. The counter shaft 59 is connected with the gear wheel 58 by a pawl and ratchet (Fig. 7) which permits, as usual, the counter being turned back to zero without requiring the rotation of the shaft 56 and wheel 55. The disk 70 may be turned back to zero position by means of the knob 71 and at the same time used to turn the wheel 61 to zero position, to accomplish which purpose I provide the back of the disk 70 with a pin 73 (Fig. 5) adapted when

the knob 71 is pressed inwardly against the stress of the spring 74, to enter a groove 75 in the wheel 61 and during the rotation of the disk engage a shoulder at the end of said groove and thus connect the disk and wheel together and enable the disk on its backward rotation to restore the wheel 61 to zero position. Preparatory to the setting back of the disk 70 and wheel 61, the arm 67 may be pressed outwardly from the ratchet 65 and cam 64 if desired.

I provide for each wheel 55 a spring-pressed brake-wheel 76 so as to assume accuracy in the intermittent movements thereof, and said brake-wheel may if desired be relieved from said wheel 55 preparatory to the setting back of the disk 70 and wheel 61. The wheel 76 is mounted in one arm of a bell-crank lever 77 whose other arm is engaged by a spring 78, and said wheel 76 is of a diameter to enter between the teeth of the wheel 55 and by engaging two of said teeth at their facing sides (Fig. 4) afford an efficient brake. The brake-wheel 76 is forced outwardly by the successive teeth of the wheel 55 to allow said teeth to ride by it as the successive coins by pressing against the lower teeth of said wheel 55 set the wheel in motion, and as a tooth of the wheel 55 passes downwardly below the transverse center of the wheel 76 said wheel 76 by reason of its spring pressure acts against the upper edge of said tooth and forces the wheel 55 to complete its intermittent movement, whereby the wheel 76 becomes efficient in assuring accurate intermittent movements of the wheel 55 and in arresting said wheel at the end of each of its intermittent movements.

The invention is not limited to the employment of any special character of coin-counting and computing mechanisms, since mechanisms for performing such duties are well known and of varied organization. Such novel features, however, as may be present in the special computing mechanism shown in the drawings, are to be made the subject of a separate application for Letters Patent.

I have only shown a few numbers on the wheel 61 and disk 70, since the numbers on said wheel and disk may vary. When pennies are being registered, the wheel 61 will on each rotation be used to count and indicate them up to 100 and then on the last or one-hundredth move of the wheel 61, the trip or shoulder 170 on the cam 64 will permit the pawl 66 to move the ratchet 65 one space and cause the disk 70 to move one space and register "1" or one dollar. When ten-cent pieces are being registered, each move of the disk 70 will represent "10" or ten dollars. When twenty-five cent pieces are being registered, I prefer to equip the cam 64 with five shoulders or trips, as shown

- in Fig. 9, so that the ratchet 65 may cause the disk 70 to register at each move "5" or five dollars, or twenty-five dollars on each complete rotation of the wheel 61. When the cam shown in Fig. 9 is employed in the mechanism for counting five cent pieces, the disk 70 will represent on each move "1" or one dollar, or five dollars on each complete rotation of the wheel 61.
- 10 The operation of the machine made the subject hereof will be understood without special further description thereof. I regard it important that the several screens or coin plates project laterally one beyond another in series, since such arrangement permits a complete inspection of the coins on the plates, the manual moving about of the coins to cause the proper ones to descend through the plates, the convenient brushing or moving of the coins which properly remain on the plates to the respective hoppers at the edges thereof, the detection, by the sense of touch, of counterfeit coins and the use of stationary coin or screen plates.

In Fig. 4 I illustrate the presence of two coins of the wrong denomination or of less than the proper diameter in the guideway or chute 35, so as to indicate the function 30 of the wheel 38 in discarding them laterally. Each coin forced laterally by a wheel 38 from a guideway or chute 35 falls on the next lower coin-plate or screen and either remains on or passes through the same, as 35 may be proper.

The invention is not limited to details of form or construction, since I desire adequate protection for my invention.

What I claim, is:

- 40 1. In a machine of the character described, a vertical series of coin-sorting plates having openings therein for the escape of the coins not to be held thereon, said plates being partly below and extending horizontally beyond one another in series 45 and the horizontal portions of said plates being freely separated from each other and exposed to admit the hand of the operator thereto for manually moving the coins about thereon and causing the coins not to be held thereon to pass through the openings therein.
- 55 2. In a machine of the character described, a vertical series of coin-sorting plates having openings therein for the escape of the coins not to be held thereon, said plates being partly below and extending horizontally beyond one another in series 60 and the horizontal portions of said plates being freely separated from each other and exposed to admit the hand of the operator thereto for manually moving the coins about thereon and causing the coins not to be held thereon to pass through the openings therein, and said plates below the top

one having downwardly inclined inner portions leading and for directing the coins falling thereon to said exposed horizontal portions.

3. In a machine of the character described, a vertical series of coin-sorting plates having openings therein for the escape of the coins not to be held thereon, said plates being partly below and extending horizontally beyond one another in series 70 and the horizontal portions of said plates being freely separated from each other and exposed to admit the hand of the operator thereto for manually moving the coins about thereon and causing the coins not to be held thereon to pass through the openings therein, and exposed hoppers at the outer edges of said plates into which the coins detained thereon may be manually moved for their 80 automatic discharge.

4. In a machine of the character described, a vertical series of coin-sorting plates having openings therein for the escape of the coins not to be held thereon, said plates being partly below and extending 90 horizontally beyond one another in series and the horizontal portions of said plates being freely separated from each other and exposed to admit the hand of the operator thereto for manually moving the coins about thereon and causing the coins not to be held thereon to pass through the openings therein, exposed hoppers at the outer edges of said plates into which the coins detained thereon may be manually moved for their 95 automatic discharge.

5. In a machine of the character described, a vertical series of coin-sorting plates having openings therein for the escape of the coins not to be held thereon, said plates being partly below and extending 100 horizontally beyond one another in series and the horizontal portions of said plates being freely separated from each other and exposed to admit the hand of the operator thereto for manually moving the coins about thereon and causing the coins not to be held thereon to pass through the openings therein, exposed hoppers at the outer edges of said plates into which the coins detained thereon may be manually moved for their 105 automatic discharge, guideways or chutes leading from said hoppers, means for forcing the coins one after another along said guideways, and means at each guideway for permitting the lateral discharge therefrom 110 of a coin of the wrong denomination therefor.

5. In a machine of the character described, a vertical series of coin-sorting plates having openings therein for the escape of the coins not to be held thereon, said plates being partly below and extending 115 horizontally beyond one another in series and the horizontal portions of said plates being freely separated from each other and exposed to admit the hand of the operator thereto for manually moving the coins about thereon and causing the coins not to be held thereon to pass through the openings therein, exposed hoppers at the outer edges of 120 said plates into which the coins detained thereon may be manually moved, guideways or chutes leading from said hoppers, and means for forcing the coins one after another on edge along said guideways.

6. In a machine of the character described, a vertical series of coin-sorting plates having openings therein for the escape of the coins not to be held thereon, said plates being partly below and extending 125

horizontally beyond one another in series and the horizontal portions of said plates being freely separated from each other and exposed to admit the hand of the operator thereto for manually moving the coins about thereon and causing the coins not to be held thereon to pass through the openings therein, exposed hoppers at the outer edges of said plates into which the coins detained thereon may be manually moved, guideways or chutes leading from said hoppers, means for forcing the coins one after another on edge along said guideway, independent receptacles to receive the coins from said guideways, and means for simultaneously discharging all said receptacles into bags or the like.

7. In a machine of the character described, a vertical series of coin - sorting plates having openings therein for the escape of the coins not to be held thereon, said plates being partly below and extending horizontally beyond one another in series and the horizontal portions of said plates being freely separated from each other and exposed to admit the hand of the operator thereto for manually moving the coins about thereon and causing the coins not to be held thereon to pass through the openings therein, exposed hoppers at the outer edges of said plates into which the coins detained thereon may be manually moved, guideways or chutes leading from said hoppers, means for forcing the coins one after another on edge along said guideways, and receptacles to receive the coins from said guideways, said receptacles having bottoms which may be opened and at their outer faces doors.

8. In a machine of the character described, a vertical series of coin - sorting plates having openings therein for the escape of the coins not to be held thereon, said

plates being partly below and extending horizontally beyond one another in series and the horizontal portions of said plates being freely separated from each other and exposed to admit the hand of the operator thereto for manually moving the coins about thereon and causing the coins not to be held thereon to pass through the openings therein, and exposed hoppers at the outer edges of said plates into which the coins detained thereon may be manually moved for their automatic discharge, said plates at the entrance to said hoppers being deflected downwardly and outwardly to tilt the coins and direct the same on edge thereto.

9. In a machine of the character described, a vertical series of coin - sorting plates having openings therein for the escape of the coins not to be held thereon, said plates being partly below and extending horizontally beyond one another in series and the horizontal portions of said plates being freely separated from each other and exposed to admit the hand of the operator thereto for manually moving the coins about thereon and causing the coins not to be held thereon to pass through the openings therein, exposed hoppers at the end-ports of the outer edges of said plates into which the coins detained thereon may be manually moved, guideways or chutes leading from said hoppers, and means for forcing the coins of a predetermined denomination one after another along said guideways and ejecting coins of an improper denomination.

Signed at New York city, in the county of New York and State of New York, this 10th day of February, A. D. 1913.

CHARLES S. BATDORF.
